UNITED STATES PATENT OFFICE.

JOHN R. BALL, OF DURANGO, COLORADO.

BALL-MILL LINER.

1,307,952.

Specification of Letters Patent. Patented June 24, 1919.

Application filed September 19, 1918. Serial No. 254,783.

To all whom it may concern:

Be it known that I, JOHN R. BALL, a citizen of the United States, residing at Durango, in the county of La Plata and State 5 of Colorado, have invented certain new and useful Improvements in Ball-Mill Liners; and I do declare the following to be a full, clear, and exact description of the invention, such as will enable others skilled in the art 10 to which it appertains to make and use the same.

My invention relates to the class of mills used principally for grinding ore to a pre-determined mesh and employing a rotary 15 grinding chamber in which a plurality of crushing balls are provided. Heretofore, considerable difficulty has been encountered with the common types of linings employed for such mills and since it is often necessary 20 to remove an old lining and install a new one, it has been a source of great trouble. It is therefore the object of my invention to provide a novel type of lining for ball mills which is free of a number of objections here- 25 tofore existing.

With the foregoing object in view, the invention resides in the novel features of construction and unique association of parts hereinafter fully described and claimed, and 30 illustrated in the accompanying drawings.

Figure 1 is a vertical longitudinal section of a ball mill provided with the improved lining.

Fig. 2 is a vertical transverse section on the 35 plane of the line 2—2 of Fig. 1.

Fig. 3 is a side elevation of one of the segments of the end lining.

Fig. 4 is an elevation of one of the lining 40 rings against which the segments of the end lining abut.

Fig. 5 is a detail section showing the bolt and washers used in securing the end linings in place.

Fig. 6 is a view similar to Fig. 2 but illustrating a different form of construction.

Fig. 7 is a vertical section on the plane indicated by the line 7—7 of Fig. 6.

The construction shown in Figs. 1 to 5 will first be described. To this end, the 50 numeral 1 designates a grinding cylinder preferably of two part construction bolted together at 2, the ends of said cylinder being provided with tubular trunnions 3 and 4, the former having a spiral collecting head 5 for 55 feeding the material to be ground into said trunnion, while the trunnion 4 is provided

with a discharge head 6, it being through said last named trunnion that the ground material is discharged from the mill. Suitable bearings 7 are employed for the trunnions 3 and 4 and the cylinder 1 may be rotated by any preferred means such as the chain 8 driven from the counter shaft 9 which may in turn be rotated by any preferred means. A belt pulley 10 is shown for 65 this purpose.

The lining for the peripheral wall of the grinding chamber 1 consists of a plurality of arcuate plates 11 disposed edge to edge and extending from one end of the cylinder 70 to the other end thereof. One edge of each lining plate 11 is provided in one of its outer corners with a groove 12 while the other edge of the plate is equipped on the corresponding corner with a tongue 13, the several tongues being received in the grooves of the adjacent plates as shown clearly in Fig. 2. The grooved edges of the plates 11 are provided with ribs 14 extending throughout the length of said plates and projecting 75 beyond the inner sides of the latter for co-action with the crushing balls (not shown) in grinding the ore or the like. No bolts whatever or other fastening means are passed through the lining plates 11, this being a 80 decided advantage over certain other forms of linings commonly secured by bolts. Bolts are required however for securing the end linings in place, but these linings are made to perform not only their usual functions, 85 but in addition are disposed to secure the lining plates 11 in place and to prevent circumferential creeping thereof.

Each end lining consists of a center lining ring 15 secured to the cylinder end by 95 bolts 16, and a plurality of segmental plates 17 resting against the peripheral edge of the ring 15, the peripheral edges of said plates 17 bearing against the inner sides of the lining plates 11 to retain them against the cylinder wall and being provided with notches 18 forming seats which receive the ribs 14, thus holding the plates 11 against circumferential creeping. Bolts 19 are provided to 100 secure the plates 17 to the ends of the cylinder and the heads of these bolts, as well as those of the bolts 16, are by preference counter sunk as shown in Fig. 2. Between the nuts 20 of the several bolts 16 and 19 and the cylinder ends, flat washers 21 and cone 110 washers 22 are preferably employed as detailed in Fig. 5, said cone washers tightly

closing the outer ends of the openings through which the bolts pass.

The tubular trunnions 3 and 4 are preferably provided with one-piece tubular linings 23 which may be removed and replaced when required, the inner ends of said linings abutting the rings 15, while the outer ends thereof bear against the heads 5 and 6. By this arrangement, the linings 23 are held 10 against both inward and outward shifting, yet by removing the heads, said linings may be easily withdrawn when required to permit new ones to be substituted. It will also be clear that the lining of the cylinder 1 15 may be removed, repaired, replaced, etc., with ease and in a comparatively short time, it being important that no means other than the end linings are provided for securing the lining plates 11 in place and for preventing 20 creeping thereof, since this not only permits quick removal and replacing of said plates 11, but leaves the wall of the grinding cylinder free of cracks and the like through which the powdered material may sift.

25 The form of the invention shown in Figs. 6 and 7 is slightly different from that illustrated in the other views, in that the lining sections 11^a are not tongued and grooved together, and the arrangement of the seats 18^a 30 is slightly different. Also, an annular rib 24 is preferably formed on each cylinder end to abut the segmental plates 17^a and the rings 15^a as shown.

From the drawings I have shown and in 35 the foregoing described two forms of my invention which have proven to be commercial successes, but I wish it understood that I am not restricted to the exact details shown and described, as will appear from an analysis of the invention as claimed.

I claim:

1. In a ball mill, the combination with a rotary cylinder having a grinding chamber therein; of an internally ribbed lining lying flat against and unsecured to the peripheral wall of said chamber, other linings for the ends of said chamber lying flat against said ends and having peripheral notches receiving the ribs of said wall lining to prevent circumferential creeping of the latter, and means securing said end linings to the ends of said chamber, said end linings being the sole securing means for said ribbed wall lining.

2. In a ball mill, the combination with a rotary cylinder having a grinding chamber therein; of a lining for the peripheral wall of said chamber unsecured thereto and composed of plates lying flat against said wall in abutting edge to edge relation and extending from one to the other of the end walls of said chamber, said plates having ribs on one edge transverse to the direction of rotation of the cylinder, and overlapping the other edges of adjacent plates, end linings for the ends of said chamber formed of segmental plates whose peripheral edges bear against the inner sides of said peripheral lining to secure it in place, said end lining plates having notches in their edges receiving said ribs to hold said peripheral lining against circumferential creeping, and means securing said segmental plates flat against the ends of the grinding chamber, said end linings being the sole securing means of said wall lining.

In testimony whereof I have hereunto set my hand.

JOHN R. BALL.
